WEED BURNER

Horace E. Woolery, St. Paul, Minn.; Myra Lillian Woolery, executrix of said Horace E. Woolery, deceased, assignor to Woolery Machine Company, Minneapolis, Minn., a corporation of Minnesota

Application May 14, 1943, Serial No. 486,973

12 Claims. (Cl. 126—271.2)

1

This invention relates to improvements in machines for burning the weeds and grasses along a railway road bed.

The primary object of my invention is to provide for this purpose a machine of small, compact and comparatively simple form, adapted to travel along the railway with its motive power provided by the usual small power car used in maintenance work or by other means, and which includes a burner or flame throwing head which may be readily adjusted to any required positions for burning the weeds over the tie area as well as outside of the ballast lines. The machine itself is designed for convenient operation by one man, and to carry its own fuel supply for burner and operating motor.

Another object is to provide a machine of this kind embodying a novel and effective, turret-like mounting for the burner mechanism, permitting the entire assembly to be readily oscillated and swung about as required for the proper positioning of the burner head, and including conveniently operable brake mechanism for locking the parts in their adjusted positions.

Still a further object is to provide a machine of this kind having novel and practical improvements in its burner fuel feed system, in the burner head raising and lowering mechanism and other details contributing to the provision of a simple, durable and practical device for the purpose.

These and other more detailed and specific objects will be disclosed in the course of the following specification, reference being had to the accompanying drawings, in which—

Fig. 1 is a side view of my weed burner as supported upon a section of railway track, and showing the burner head and its tube in an elevated or transport position.

Fig. 2 is an enlarged, fragmentary vertical and longitudinal sectional view through a lower part of the machine showing a part of the fuel feed line and its extension through the pivot member about which the burner frame oscillates.

Fig. 3 is a plan view of the weed burner, showing the burner head, and the frame from which it is extended, swung toward one side of the car.

Fig. 4 is an enlarged vertical sectional view of the brake and operating mechanism for raising and lowering the burner tube.

Fig. 5 is an enlarged and fragmentary side elevation of a lower part of the burner frame and associated parts, showing the brake mechanism for locking the same in any adjusted position, this view showing the frame supporting track and a part of the car in vertical section.

2

Fig. 6 is an enlarged vertical sectional view along the line 6—6 in Fig. 1.

Fig. 7 is an enlarged vertical sectional view of a lower corner portion of the burner frame illustrating the manner in which the brake shoe or bar is held in place.

Fig. 8 is a sectional view along the line 8—8 in Fig. 7.

Fig. 9 is an enlarged sectional view along the line 9—9 in Fig. 1.

Referring now more particularly and by reference characters to the drawings, it will be seen that my machine comprises a base frame in the form of a small car 10 having small flanged wheels 11 journaled at its corners by means of which it may travel on the usual railway rails 12. A cover sheet 13 is provided on the car and suitably braced and supported to act as a platform upon which the operator may stand to operate and control the burner. At one end an extension or apron 14 of the car is provided and this extension is lowered below the level of the car itself and provided with a rail 15, this end of the car being the forward end when the machine is traveling over the rails. Any suitable hitch (not shown) may be provided at this end of the car for the connection thereto of a power car (also not shown) or other suitable draft device for pulling car 10 along the track. The extension 14 is of such size as to nicely receive and carry two standard oil drums or barrels 16 providing fuel for the burner.

Arranged intermediate the sides of the car 10 and toward but some distance from its rear end is a turret 17 having a flat circular top 18 spaced above the level of the platform 13 and supported on this turret top is a burner frame or carrier frame designated generally at 19. Said frame includes a base made up of parallel beams or bars 20 which are joined by a transversely and horizontally extending plate 21 bearing upon the turret top. A tubular pivot member 22 is welded in the center of the turret top 18 and extends upwardly through an opening 23 in the plate 21 thus forming a pivot for the frame 19 whereon it may be oscillated in a horizontal plane above the car. This pivot is located somewhat off center with reference to the length of the base of the burner frame as clearly shown so that the frame does not balance at this point.

50. An arcuate or rounded, and slightly more than semicircular, supporting track 24 is carried by suitable brackets 25 on the car 10 and extends around the rear end and the sides thereof, being centered about the pivot axis of the burner frame 55 19 and disposed at a level such that the end of the

frame will just clear it. Rollers 26 are provided at each side of the frame at this end and run upon the track permitting the frame to be easily swung around in a half circle from one side of the car to the other. End braces 27 extend between the ends of the track 24 and adjacent sides of the car and have upward humps 28 which will engage the rollers to prevent them from running off the track ends.

The burner frame 19 includes upright corner posts arranged in pairs 29 and 30, at its opposite ends, and between these posts, on the base beams 20, are mounted the conventional burner mechanism including as its main elements a blower 31, a fuel pump 32 and an engine or power unit 33 for operating these parts. Suitable control valves and piping, as well as belt connections between the units 31, 32 and 33 are also provided but since these parts are conventional in operation and arrangement they will not be described in detail herein. At one point however the fuel supply means is novel and will now be described.

The fuel oil is taken from either of the drums 16 through a strainer 34 at the end of a flexible tube 35 which is connected to the upper end of a pipe 36^a within a standpipe 36. This standpipe is erected at the front end of the car 10 at the center thereof and at its lower end is open through a port 36^b. A pipe 37 is connected to the lower end of the pipe 36^a, said pipe 37 extending forwardly beneath the platform 13 to a point beneath the center of the turret 17 whereat it is turned upwardly as at 38 through the turret and through the tubular pivot member 22. A swing joint 39 is attached to the upper end of the pipe from which a pipe 40 leads off to other parts of the burner mechanism, ultimately reaching the pump 32 and so that fuel will be delivered under pressure therefrom to a supply pipe 41 which will be described in more detail later herein. The swing joint 39 turns freely on the upper end of the pipe 38 as the burner frame 19 is swung about and provides for fuel feed from the drums 16 without any hanging flexible lines over the car platform which would be in the way of the operator standing thereon. When the strainer 34 is not in use, such as when the drums 16 are being replaced after emptying, it may be placed in a drain cup or pocket 42 on the lower end portion of the standpipe 36 and the oil therefrom will drain through an opening 43 into the pipe and out through the port 36^b beneath the car.

An air tube 44 leads from the blower 31 outward endwise from the burner frame between the corner posts 30 thereof and terminates in a swing joint 45 by which a burner tube 46 is pivotally mounted for up and down adjustments at its free end. A burner head 47 is provided on this free end of the tube 46 and has a flame opening 48 through which issues the flame employed to burn the weeds. The fuel supply pipe 41 is connected by a flexible tube 49, located at the pivot center 50 of swing joint 45, to a pipe 51 leading out to the end of the tube 46 where it enters the tube and is connected therein to any suitable type of atomizer (not shown) so that the air supplied through the tube from the blower 31 will combine with the fuel to form an inflammable mixture and provide the necessary flame.

A suitably trussed boom member 52 is secured to and between the upper ends of the burner frame corner posts 29-30 and extends at one end 53 outward over the burner tube 46. A sprocket chain 54 is attached at one end at 55 to the outer end of the burner tube and extends therefrom up-

wardly over an idler roller or sprocket 56 in the extremity of the boom end 53, thence lengthwise along the upper member 57 of the boom and over a sprocket 58 at the other end thereof. From this sprocket 58 the chain 54 is doubled back beneath the beam and passed over a roller 59 which is connected at 60 to a tension spring 61, the chain then again turning back beneath and extending to a point of attachment 62 to the upper portions of the corner posts 29. The opposite end of the spring 61 is connected at 63 to the ends of brackets 64 extended from the corner posts 30 out beneath the boom end 53 and connected thereto by braces 65.

The sprocket 58 is positioned between two bearing plates 66 (Figs. 1 and 4), which are secured atop the upper ends of the burner frame corner posts 29, and the sprocket is secured to the tubular extension 67^a of the spider or hub 67 of a brake or clutch mechanism 68 which extension is journaled in bearings 69 in the plates. Journaled through this hub 67 and its tubular extension 67^a is a shaft 70 which at one end carries a crank or handle 71 and at its other end a collar 72 which prevents endwise displacement. An inner cone 73 is secured to, or formed integrally on, the hub 67 and fits into a rigidly supported outer cone 74 carried by brackets 75 from one plate 66. An expansion coil spring 76 is placed over the shaft 70 between the handle 71 and the end of the hub 67 and urges the latter endwise in such manner as to bring the inner cone 73 normally into tight frictional engagement with the outer cone 74. A diametrically extended pin 77 in the shaft 70 enters at its ends into openings 78 in the hub 67, which openings have angularly extending cam surfaces 79 so arranged that rotation of the shaft, by handle 71, in either direction a short distance will cause a camming action endwise on the hub urging it against the spring 76 and loosening the inner cone from the outer. Continued rotation of the handle will then cause the shaft to turn the now released hub 67 and rotate the sprocket 58. Such rotation of the sprocket will either pull in or pay out the chain 54 raising or lowering the burner tube 46 about its swing joint 45, and when the handle is released the spring 76 will immediately reassert itself bringing the cones 73-74 back into tight frictional engagement to lock the burner tube in its adjusted vertical position. This brake or clutch obviously permits one hand raising and lowering operation without the actuation of a separate brake with the other hand. The function of spring 61 is to partially support and counterweight the burner tube and head, facilitating their up and down adjustment.

The rollers 26 are supported in brackets 80 extending laterally from the lower ends of the corner posts 30 so that the rollers engage the track 24 outwardly of the frame as best seen in Fig. 6. Arranged between these rollers and beneath this end of the frame is a brake shoe or bar 81 having its center web overlying the track and on its underside carrying a strip of brake lining material, as indicated at 83. The ends of the bar having upstanding, perforated ears 84 which rest loosely in the channels 85 at the outer sides of the corner posts 30 (Fig 7) and to which are connected the lower ends of tension coil springs 86 attached at upper ends 87 to the posts. These springs and the ears 84 pull the brake bar upwardly and prevent its outward displacement as will be evident. The corner posts 30 are made

up from conventional channel irons to provide the channels 25 aforesaid.

The brake bar 81, inwardly of the corner posts, has upstanding pins 88 which loosely and upwardly engage openings 89 in the ends of the burner frame sides 20 and permit the bar to move upward and downward somewhat, such movement while keeping the bar parallel with and flat against the upper surface of the track permitting it to be urged downwardly to bring the brake lining 83 into braking engagement with the track. The springs 86 normally draw the bar upwardly to free the brake lining from the track.

A bracket is provided comprising spaced arms 90 secured at lower ends to brake operating toes or levers 91, these arms being pivotally connected at upper ends at 92 to an operating rod 93 and being also biased by a retractile coil spring 94 to normally hold and tightly press the brake bar 81 and its brake lining flat against the track 24. The toes or levers 91 are located between the brake bar and the undersides of the burner frame members 20 and have openings 91a loosely clearing the pins 88. As a result, when the bracket arms 90 are pulled by the spring 94, the toes 91 are canted (Fig. 8) and pry the brake bar downwardly to braking position. The spring 94 is connected at 95 to the upper ends of the arms and at its other end is shown as conveniently attached at 96 to the blower 31. The operating rod 93 extends lengthwise in the burner frame toward the end opposite the brake mechanism and is pivotally connected thereto by a pin 97 to the lower ends of links 98 which hang from pivotal connections at upper ends 99 between the corner posts 29. A cam member 100 is formed, or provided, at the end of a brake operating arm 101 pivoted at 102 between the posts 29 and this cam member has two spaced shallow notches 103 for selectively engaging the pin 97. When thus engaged with the pin 97 the cam member 100 will exert an endwise thrust upon the operating rod such that the toes 91 release their downward pressure on the brake bar 81 in which condition the braking pressure on the track 24 will be released. When the operating arm 101 is swung either upward or downward, however, the cam member 100 may be caused to clear the pin 97 whereupon the end thrust on the rod 93 will be released and the tension of the spring 94 will oppositely rock the toes 91 to pry downwardly on the brake bar to press the brake lining tightly against the track thus applying braking forces sufficient to prevent travel of the burner frame thereover.

Actually the tension of the spring 94 and the prying or cramping action of the toes 91 on the brake bar 81, is sufficient to elevate this end of the burner frame slightly, carrying the rollers 26 upwardly clear of the track, as seen in Fig. 7, to place all of the weight at this point against the brake lining. Positive braking is thus insured.

The brake operating arm 101 has four positions in use, in two of which the notches 103 are respectively engaged with the pin 97 and the brake is released. In one of such positions, that shown in full lines in Fig. 5, the arm extends downwardly, and of course endwise from the burner frame. The arm carries at its end a U-shaped yoke member 104 which, when the arm is in this position, may engage the thigh of an operator standing on the car and which will enable him to exert sideward pressure on the

arm, without using his hands, and sufficient to oscillate the burner frame about its upright pivot and bring it to any desired position. In the other brake releasing position the arm extends upwardly too high for this operation but may be adjusted by hand.

When the brake is applied the operating arm 101 extends either upwardly or downwardly from these described positions as shown in the dotted lines in Fig. 5.

The use and operation of the machine will, it is believed, be apparent from the foregoing. The burner head 41, from which issues the flame, may be readily adjusted in the horizontal plane through an arc of approximately one hundred and eighty degrees to cover and burn weeds along the entire tie area or outwardly thereof at each side and may be locked in any such adjusted position by the brake engaging the track 24. On the other hand, when this brake is released, the rollers 26 traveling on this track permit the comparatively heavy burner frame and all of its supported parts to be easily swung around by the operator. The burner head may also be readily raised and lowered to properly adjust the spread of the flame and will be automatically unlocked and locked by the cone clutch mechanism of Fig. 4 without attention on the part of the operator. The machine is obviously well suited to one man operation and requires only a small draft force, such as a power car which may of course itself be operated by one other man to pull the machine along the track at proper speed. The burner head may be raised or lowered while being simultaneously swung to either side thus rapidly adjusting the flame spread and direction to meet all conditions.

The burner tube 46, outwardly of the swing joint 45, is arranged to swivel or oscillate about its axis and for this purpose the inner or forward end of the tube is received and frictionally engaged by a clamp band 105 which is tightly affixed around a stub end 106 of the swing joint structure. Journaled in brackets 107 alongside the band 105 is a shaft 108 having a universal joint or other suitable flexible connection 109, adjacent and alongside the pivot axis of the swing joint, with an operating shaft 110 which extends forwardly through the burner frame and carries a crank 111 at its forward end. This operating shaft is suitably supported in the frame and the crank 111 is placed at the forward end of the frame convenient to the hand of the operator, as he stands on the forward end portion of the car for operating the brakes previously described.

The end of the shaft 108 carries a lever 112 (Fig. 9) which is connected by a link 113 to a lug 114 secured to the adjacent side of the burner tube 46. This link connection is such that oscillation of the shaft 108, by crank 111, will pull or push upon the link 113 exerting tangential forces on the burner tube sufficient to oscillate it about its axis in the clamp band 105, such movements angling the burner head flame opening 48 upward to one side or the other from its normal lower position as will be readily apparent. The flame issuing from this burner head may thus be turned square toward and against the banks sometimes found alongside the road bed to more evenly spread the flame thereover.

This swivel adjustment of the burner head may also be carried out simultaneously with the raising or lowering and sideward swinging of the

burner previously described, the joint 109 providing for the movement of shaft 108 with the burner tube without interfering with its operation by crank 111.

The pipe 51, and particularly the flexible connection 49 thereto, have sufficient play to permit the aforesaid swiveling movement of the burner tube and head.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. In an apparatus of the character described and including a supporting platform, a frame pivotally supported at one end on the platform for horizontal swinging movements at its other end with respect to the platform, a substantially semi-circular track supported on the platform beneath the swinging end of the frame and centered about the pivot axis upon which the frame swings, wheels on the frame adapted to travel along said track as the frame swings, selectively applicable brake means on the frame and operative when applied to bear downwardly on the track and elevate the wheels clear of the track, and a flame projector on the frame and movable therewith.

2. In an apparatus of the character described and including a supporting platform, a frame pivotally supported at one end on the platform for horizontal swinging movements at its other end with respect to the platform, a curved track on the platform centered about the pivot axis on which the frame swings and extending beneath the swinging end of the frame to support the same, brake mechanism carried by the frame for engaging the track, spring means normally applying said brake mechanism to lock the frame with respect to the track, manually operative means for overcoming said spring means to disengage the brake mechanism from the track and a flame projector on the frame and movable therewith.

3. In an apparatus of the character described and including a supporting platform, a frame pivotally supported at one end on the platform for horizontal swinging movements at its other end with respect to the platform, a curved track on the platform centered about the pivot axis on which the frame swings and extending beneath the swinging end of the frame to support the same, a brake shoe yieldably supported beneath the frame over the track, a movable member having toes disposed between the frame and said shoe and adapted when canted to force said shoe downwardly into braking engagement with the track, means for moving the member to cant the toes thereof, and a flame projector carried by the frame and movable therewith.

4. In an apparatus of the character described and including a supporting car having a platform, a frame pivotally supported at one end on the platform for horizontal swinging movements at its other end with respect to the platform, a curved track on the platform centered about the pivot axis on which the frame swings and extending beneath the swinging end of the frame to support the same, a brake shoe yieldably supported beneath the frame and over the track, an oscillatable brake applying member having toe portions disposed between the frame and

brake shoe and loosely connected to the frame for canting movement such as to pry the shoe downward from the frame into engagement with the track, means for moving said brake applying member, and a flame projector carried by the frame and movable therewith.

5. In an apparatus of the character described and including a support and a frame having several hand controls at one end and said frame being pivotally supported on said support for swinging movements by an operator stationed adjacent that end, means for releasably locking the frame against such movements and including a member extending from the frame and having a yoke adapted to be engaged by the operator's thigh when the member is adjusted to unlock the frame whereby he may swing the frame while his hands are occupied with the said controls, and a member carried by the frame to be swung thereby.

6. In an apparatus of the character described and including a support and a frame having several hand controls at one end and said frame being pivotally supported on said support for swinging movements by an operator stationed adjacent that end, means for releasably locking the frame against such movements and including a member extending from the frame and having a yoke adapted to be engaged by the operator's thigh when the member is adjusted to unlock the frame whereby he may swing the frame while his hands are occupied with the said controls, said member being also selectively positionable in another position at which the frame will also be unlocked and the member adapted for hand operation to swing the frame, and a work member carried by the frame.

7. In an apparatus of the character described and including a support and a frame pivotally supported on the support for swinging movements under control of an operator stationed adjacent the frame and said apparatus including at least two hand controls for actuation by said operator, a member extending from the frame adjacent said operator's station, means on the said member for engagement with the operator's leg whereby he may exert leverage to swing and adjust the frame while his hands are simultaneously occupied with said hand controls, and a work member carried by the frame.

8. In an apparatus of the character described and including a support and a frame pivotally supported thereon for swinging movements under control of an operator stationed adjacent the frame and said apparatus including at least two hand controls for actuation by said operator, a member extending from the frame adjacent said operator's station, said member being selectively adjustable to one position for hand operation and another position for operation by the leg of the operator when his hands are occupied with said hand controls, and a work member carried by the frame.

9. In combination with a wheeled car having a floor, a curved track on the floor, a frame pivotally supported on the floor for oscillating movements at one end over said track, a flame projecting means carried by and oscillating with the frame, brake means adapted to engage the track and lock the frame in an adjusted position, means on the frame for supportably engaging the track, and the said brake means being operative to so engage the track as to elevate the frame end and lift said supporting means from the track when the brake is applied.

10. In combination with a wheeled car having a floor, a curved track on the floor, a frame pivotally supported on the floor for oscillating movements at one end over said track, a flame projecting means carried by and oscillating with the frame, brake means carried by the frame for engaging the track to lock the frame in an adjusted position, the said brake means having a friction surface adapted to be pressed against the upper surface of the track, an oscillatable brake frame having means for pressing said friction surface against the track, and means for oscillating said brake frame to apply and release the brake.

11. In combination with a wheeled car having a platform, a curved track on the platform, a frame pivotally supported on the platform for oscillating movements at one end over the track, a flame projecting means carried by and oscillating with the frame, brake means carried by the frame at the end traveling over said track to lock the frame against movement, means at the other end of the frame operatively connected to the brake means for actuating the same, the said brake actuating means including an arm having a yoke member adapted for engagement with an operator's leg whereby the frame may be oscillated by the operator without use of his hands when the brake means is released.

12. In combination with a wheeled car having a platform, a frame pivotally supported adjacent one end on the platform for swinging movements at its other end, a flame projector carried by and swingable with the frame, and an arm extending from the first mentioned end of the frame and having means for engagement with the leg

of an operator stationed on the platform whereby the frame may be swung on its pivotal support by said operator, without use of his hands, and by exerting sideward forces on the arm.
